UNITED STATES PATENT OFFICE.

JOHN H. WERTLEY, OF HAMBURG, PENNSYLVANIA.

SNOWPLOW.

Application filed February 15, 1928. Serial No. 254,554.

This invention relates to a snow plow, the general object of the invention being to provide means for lifting the snow by the plow and then moving the snow to either side of the plow so that the snow is not packed by the plow and resistance offered by the snow to the plow is practically eliminated, this result being secured by forming the plow with an inclined top portion up which the snow passes from a cutting blade at the lower front end of the incline and a scraper-like blade adjustably mounted on the incline for deflecting the snow moving up the incline to either side of the cut being made by the plow. The adjustable blade can also be set transversely of the incline to push the snow ahead of the plow and it can also be used to cut down the walls of a drift and to remove the piled up snow at the sides of a cut previously made by the plow.

A further object of the invention is to provide means for so connecting the plow with a tractor that the tractor will move the plow in wheelbarrow fashion, with adjustable shoes at the front end of the plow so that the weight is distributed between the shoes and the tractor, thus reducing the resistance offered by the plow to the tractor.

A further object of the invention is to provide a hydraulic lift actuated by the tractor for lifting the plow and the snow piled on the same so that the snow can be removed from a drift to another point by backing the tractor, this action being somewhat similar to that of a steam shovel.

Another object of the invention is to provide wings at each side of the frame of the plow adjacent the tractor for increasing the width of cut, such wings being foldable at the sides of the frame where they will be out of the way when not in use.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a plan view of the plow attached to a tractor.

Figure 2 is an elevation.

Figure 3 is a front view with the adjustable blade set to push the snow in front of the tractor.

Figure 4 is a longitudinal sectional view with the tractor shown in dotted lines.

Figure 5 is a section on line 5—5 of Figure 2.

Figure 6 is a section on line 6—6 of Figure 2.

Figure 7 is a fragmentary plan view of the front end of the plow, showing the cutter blade in dotted lines.

Figure 8 is a section on line 8—8 of Figure 4.

Figure 9 is a perspective view of the cutter blade.

Figure 10 is a perspective view of one of the bars for connecting the plow with the tractor.

Figure 11 is a view of one of the shoes.

Figure 12 is a detail sectional view showing a shoe attached to a wing.

Figure 13 is a view of one of the movable side members for preventing snow being pushed in front of the tractor by the side wings.

In these drawings, A indicates the side members of the frame of the plow, each of which is composed of the channel bars 1 and the plates 2 so that the sides of the frame are closed and these frames are connected together by the cross bars 3. The upper edge of the front portion of each side member slopes downwardly to the front end of the member and a top plate or member 4 is fastened to said edges so that this member 4 forms an incline which lifts the snow as the plow travels along, as the member passes under the snow and causes the snow to travel up the same. This member or incline 4 is wider at its upper end than at its front or lower end, with its side edges projecting beyond the side members A. A cutting blade 5 adjustably fastened to the lower or front end of the plow by the bolts 6, the member 4 having rows of holes 7 therein adjacent its edges for receiving the bolts. This blade 5 is formed with a substantially straight flat front part 5', the front edge of which is beveled as shown and its rear portion inclines upwardly and rearwardly so that it rests flatly upon the lower part of the incline 4. A runner 7 is connected with the point of the part 5' of the blade, this runner 105 acting to cause the plow to ride over obstructions on the road surface. The lower

65

70

75

85

100

105

110

end of the member 4 is recessed, as at 8, to space this part of the member from the road surface, the recess being covered by the blade. A shoe 9 is bolted to the front 5 part of each side member for supporting the front part of the plow from the road surface, each runner being adjustable vertically by having a plurality of holes 10 therein for receiving the bolts.

10 The rear ends of the side members of the plow are attached to a tractor, such as shown at B, through means of the bars 11, each of which has an enlargement 12 at its lower end which has a hole therein to receive a 15 pivot pin 13 which projects from each side of the tractor adjacent the center thereof and near the bottom of the ground engaging element of the tractor. These bars slidingly fit in guideways formed by the channel bars 20 14 fastened to the rear end of each side member A, the rear bar being removable for permitting the bar 11 to be placed in the guideways or removed therefrom. A plate 15 is secured to the inner bar 14 of each side member 25 and forms portion of the guideway. Thus the plow is supported by the shoes and the bars 11 pivoted to the tractor in wheelbarrow fashion so that the weight is equally distributed between the shoes and the tractor 30 and the resistance offered by the plow to the tractor is reduced to a minimum. The manner of connecting the rear part of the plow with the tractor permits vertical and swinging movement of the plow in relation to the 35 tractor so that the plow can readily pass over rough roads and obstructions on the road surface and the plow can be lifted, as will be hereinafter described.

A frame 16, including a pair of vertically 40 arranged channel bars 17 forming guideways, is connected with the cross bars 3 under the rear end of the member 4 and this frame is braced by the upper and lower bars 18, the upper bars being connected with the under 45 side of the member 4 and the lower bars being connected with the cross pieces 3, with their front ends connected with the front ends of the upper bars. Runner forming pieces 19 are placed at the junction of the 50 two sets of bars, these runners being arranged under the front end of the member 4. Similar runner forming pieces 20 are also arranged at the junction of the bars 1 of the side members where the lower bars connect with the inclined bars which support 55 the member 4. As will be seen, the bars 18 form a frame for reinforcing the frame of the plow in addition to strengthening the frame 16, and the rear ends of the lower bars 18, which extend beyond the frame 16, are formed with enlarged vertical portions 21 which act as guiding means on the frame or saddle 22 which fits over the radiator of the tractor. The rear ends of the lower bars 60 18 are connected by the plates 23 with the

lower bars 1 of the side frames. A plunger or piston 24 is connected with the central part of the top piece of the frame 16 and depends therefrom midway between the guiding bars 17. A frame 25, carrying the 70 cylinder 26 for the plunger or piston 24, is slidably arranged in the guideways formed by the bars 17 and a roller 27 is carried by the lower end of this frame 25, this roller engaging the road surface. The cylinder and 75 piston form a hydraulic lift for the plow for swinging it around a horizontal axis formed by the pivot pins 13.

The cylinder is supplied with oil or other fluid by a pump 28 attached to the rear part 80 of the tractor and driven from a power take-off thereof. The pump is connected by the pipes 29 with the cylinder of the hydraulic means.

A scraper-like blade 30 is adapted to be 85 fastened to the member 4 by the bolts 31 which pass through the longitudinally extending slot 32 in the blade, the member 4 being provided with rows of holes 7' in addition to the rows 7 for receiving the bolts 90 31 so that the blade 30 can be adjusted to various positions on the member 4 and it can also be adjusted at different angles or to a position where it will extend at right angles with the member 4, as shown at dotted lines 95 in Figure 1. The blade can also be moved longitudinally on the member 4 and where the position or inclination is not to be changed, this adjustment can be made without removing the bolts, due to the slot 32. 100

A wing 33 is arranged at each side of the plow and each wing is hinged to each side frame A by having its hinge parts 34 engaging a rod 35 carried by the brackets 36 on the outer bars 1 of the side member. 105 Thus each wing is hingedly connected with each side member and it also has vertical movement as the hinge parts 34 have sliding movement on the rod 35. Shoes 37 are formed on the bottom of each wing for engaging the road surface and each wing is provided with a hook 38 at its upper end for engaging a hole 39 in the top bar 1 of the side member to hold the wing in raised and folded position. As will be seen, when the 110 wing is in this position, it will be protected from the snow by the overhanging side edge of the member 4. Each wing is supported in open position by the brace bars 40 which are pivoted to the wing and to a rod 41 carried by some of the bars 1 of the side member, each rod 41 being slidably supported so that the braces can move vertically with the wing. These wings act to widen the cut made by the plow and when in open position, they extend at an incline rearwardly so that the snow will be directed toward the sides of the cut by the wings. 115

In order to prevent snow being pushed under the plow and in front of the tractor 120

by the wings, I provide a pair of runner-like members 42 which are supported for vertical movement at the centers of the side members, these members 42 having their lower edges contacting with the road surface through the action of gravity as the plow moves over irregularities in the road surface so that they close the space between the lower edges of the side members and the road surface and thus prevent the snow from the wings passing under the plow and in front of the tractor or piling up in front of the roller 27 of the hydraulic means. As shown, these members 42 straddle the plates 23 and the lower rear cross bar 3 and are movable in the space between the lower bars 1 and the plates 2.

From the foregoing it will be seen that the plow lifts the snow instead of moving it to one side or the other so that the snow is not packed and is moved with the least resistance. As the snow passes upwardly over the member 4, it engages the blade 30 which may be set to any point intermediate the ends of the member 4 and this blade can also be set at any desired angle to move the snow to either side of the cut. By making the blade adjustable lengthwise of the member 4, it may be set to suit the depth of snow being moved and it can also be adjusted to throw the snow to one side or the other of the cut. The blade 30 can also be used to reduce the height of the snow at both or either side of a cut previously made by setting the blade as shown in Figure 1, and running the plow in the cut previously made so that the projecting part of the blade will force the top of the snow bank at one side of the cut to one side of the plow so that the plow can make a new cut alongside of the first without operating in the full depth of the snow. The arrangement shown in Figure 1 can also be used to undercut the deep drifts. In many instances, snow is piled diagonally across a road so that most of the snow is on one side of the road. By adjusting the blade 30 so that its extended part projects downwardly and outwardly, the snow is undercut by the blade and conveyed to the opposite side of the road where there is but little snow. The snow above the undercut will then fall from the top of the drift and thus reduce the excess amount of snow on one side and the snow will be conveyed to the other side. This operation will be repeated until the cleared part of the road is wide enough to travel on. The blade 30 may be placed at the top of the member 4 and at right angles to the length of said member to plow extra deep snow. When the plow is so used, the snow is lifted to the top of the drift and forced by the blade to the sides of the cut, after which the blade may be adjusted as in Figure 1 so that the piled up snow made

by the first operation can be moved back by the blade so that a new cut may be made by the plow.

By adjusting the shoes 9 downwardly, the point of the cutting blade will be raised above the road surface so that the plow can be used where the road is muddy beneath the snow.

Where the drift is so deep that the blade 30 cannot move the snow from the member 40 to the top of the drift at the side of the cut, the hydraulic means can be used to lift the plow and the snow thereon and thus break up the resistance caused by the solidity of the drift, thus making it possible for the tractor to push ahead and continue through the drift. If this is impossible, the tractor can be backed after the plow with the snow thereon has been lifted and then the snow dumped from the plow when the plow has been moved out of the drift. This action is somewhat similar to a steam shovel.

By placing the blade 30 transversely at the lower part of the member 4, the plow can be used for pushing snow ahead of the plow. This position of the blade is shown in dotted lines in Figure 1.

By adjusting the cutting blade 5 to a high position on the member 4, the depth of cut is reduced. As will be seen, either one or both of the side wings may be used or both side wings may be moved to inoperative position. These wings increase the width of cut made by the plow. The shoes 9 are placed a proper distance behind the nose 100 and cutting blade so as to allow the plow to enter the hard snow crusts and this arrangement, with the wheelbarrow action of the tractor on the plow enables the plow to operate with the minimum amount of power and maximum amount of tractor traction.

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:

1. A snow plow of the class described comprising a frame, a top member sloping downwardly and forwardly thereon, a cutting blade at the front or lower end of the top member, a scraper-like blade of greater length than the width of the top member and means for adjustably connecting the blade with the top member so that the blade can be placed at various points intermediate the ends of the top member and at various angles in relation to the top member and also adjusted longitudinally on the top member.

2. A snow plow of the class described comprising a frame, a top member sloping

downwardly and forwardly thereon, a cutting blade at the front or lower end of the top member, a scraper-like blade of greater length than the width of the top member, means for adjustably connecting the blade with the top member so that the blade can be placed at various points intermediate the ends of the top member and at various angles in relation to the top member and also adjusted longitudinally on the top member, and means for adjusting the position of the blade at the front end of the top member.

3. A snow plow of the class described comprising a frame, a top member sloping downwardly and forwardly thereon, a cutting blade at the front or lower end of the top member, a scraper-like blade of greater length than the width of the top member, means for adjustably connecting the blade with the top member so that the blade can be placed at various points intermediate the ends of the top member and at various angles in relation to the top member and also adjusted longitudinally on the top member, means for adjusting the position of the blade at the front end of the top member, and a wing hinged to each side of the rear part of the plow, means for holding each wing in extended position, and means for holding each wing in folded position.

4. A snow plow of the class described comprising a frame, a top member sloping downwardly and forwardly thereon, a cutting blade at the front or lower end of the top member, a scraper-like blade of greater length than the width of the top member, means for adjustably connecting the blade with the top member so that the blade can be placed at various angles in relation to the top member and also adjusted longitudinally on the top member, means for adjusting the position of the blade at the front end of the top member, a wing hinged to each side of the rear part of the plow, means for holding each wing in extended position, means for holding each wing in folded position, and means forming portion of the hinge for permitting vertical movement of each wing.

5. A snow plow comprising a frame, a top member connected with the front part of the frame and sloping downwardly and forwardly, a blade at the lower end of the top member, a scraper-like blade adjustably connected with the top member so that it can be placed in various positions on the top member and at various angles in relation to the top member and also adjusted lengthwise on the top member, shoes adjustably connected with the lower front portion of the frame and means for pivotally connecting the rear portions of the frame with the sides of a tractor.

6. A snow plow comprising a frame, a top

member connected with the front part of the frame and sloping downwardly and forwardly, a blade at the lower end of the top member, a scraper-like blade adjustably connected with the top member so that it can be placed in various positions on the top member and at various angles in relation to the top member and also adjusted lengthwise on the top member, shoes adjustably connected with the lower front portion of the frame, means for pivotally connecting the rear portions of the frame with the sides of a tractor, and means for permitting vertical sliding movement of the rear portions of the plow in relation to the tractor.

7. A snow plow comprising a frame, a top member connected with the front part of the frame and sloping downwardly and forwardly, a blade at the lower end of the top member, a scraper-like blade adjustably connected with the top member so that it can be placed in various positions on the top member and at various angles in relation to the top member and also adjusted lengthwise on the top member, shoes adjustably connected with the lower front portion of the frame, means for pivotally connecting the rear portions of the frame with the sides of a tractor, means for permitting vertical sliding movement of the rear portions of the plow in relation to the tractor, and means operated from the tractor for raising and lowering the front portion of the plow.

8. A snow plow comprising a frame, a top member connected with the front part of the frame and sloping downwardly and forwardly, a blade at the lower end of the top member, a scraper-like blade adjustably connected with the top member so that it can be placed in various positions on the top member and at various angles in relation to the top member and also adjusted lengthwise on the top member, shoes adjustably connected with the lower front portion of the frame, means for pivotally connecting the rear portions of the frame with the sides of a tractor, means for permitting vertical sliding movement of the rear portions of the plow in relation to the tractor, and means operated from the tractor for raising and lowering the front portion of the plow, such means comprising hydraulic means.

9. A snow plow comprising a frame, a top member connected with the front part of the frame and sloping downwardly and forwardly, a blade at the lower end of the top member, a scraper-like blade adjustably connected with the top member so that it can be placed in various positions on the top member and at various angles in relation to the top member and also adjusted lengthwise on the top member, shoes adjustably connected with the lower front portion of the frame, means for pivotally connecting the rear portions of the frame with the sides of a tractor.

the sides of a tractor, means for permitting vertical sliding movement of the rear portions of the plow in relation to the tractor, means operated from the tractor for raising 5 and lowering the front portion of the plow, such means comprising hydraulic means, and side wings hingedly connected with the rear portions of the frame, means for holding each wing in extended position, and means 10 for holding each wing in folded position.

10. In combination with a tractor having a pivot pin extending outwardly from each side thereof, a bar having its lower end pivoted on each pin, a tractor frame comprising two side members, the rear end of each side member having a guideway therein for receiving each bar, a shoe adjustably connected with the front end of each side member at the bottom thereof, a top member 15 on the front part of the frame sloping downwardly and forwardly, a cutter blade at the front end of the top member, a scraperlike blade of greater length than the width of the top member, said blade having 20 a longitudinally extending slot in its base, bolts passing through the slot and through the top member, said top member having a plurality of holes therein for receiving the bolts so that the blade is adjustably 25 connected with the top member, and means for raising and lowering the front part of the plow by the tractor.

11. In combination with a tractor having a pivot pin extending outwardly from each side thereof, a bar having its lower end pivoted on each pin, a tractor frame comprising two side members, the rear end of each side member having a guideway therein for receiving each bar, a shoe adjustably 30 connected with the front end of each side member at the bottom thereof, a top member on the front part of the frame sloping downwardly and forwardly, a cutter blade at the front end of the top member, a scraperlike blade of greater length than the width of the top member, said blade having 35 a longitudinally extending slot in its base, bolts passing through the slot and through the top member, said top member having a plurality of holes therein for receiving the bolts so that the blade is adjustably 40 connected with the top member, means for raising and lowering the front part of the plow by the tractor, such means comprising a frame having vertically arranged guideways 45 therein connected with the main frame and

arranged under the rear end of the top member, a plunger carried by the top of said frame, a cylinder, a carrying frame for the cylinder slidably arranged in the guideways, 50 said cylinder receiving the plunger, the cylinder and plunger forming hydraulic means, a pump operated by the tractor for pumping oil to the cylinder, a saddle on the radiator of the tractor and guiding means 55 connected with the hydraulic frame engaging the sides of the saddle.

12. In combination with a tractor, a snow plow comprising side members having their rear ends pivotally and slidably connected 60 with the sides of the tractor, a top member connected with the front part of the side members and sloping downwardly and forwardly, a scraper-like blade adjustably connected with the top member, shoes adjustably 65 connected with the forward ends of the side members at the bottom thereof, a side wing hingedly connected with the rear part of each side member, means for holding each wing in extended position, means for holding each wing in folded position and a runner-like member slidably supported by each side member for preventing the snow from the wings from passing under the side members in front of the tractor. 80

13. In combination with a tractor, a snow plow comprising side members having their rear ends pivotally and slidably connected with the sides of the tractor, a top member connected with the front part of the side 90 members and sloping downwardly and forwardly, a scraper-like blade adjustably connected with the top member, shoes adjustably connected with the forward ends of the side members at the bottom thereof, 95 a side wing hingedly connected with the rear part of each side member, means for holding each wing in extended position, means for holding each wing in folded position, a runner-like member slidably supported by each side member for preventing the snow from the wings from passing under the side members in front of the tractor, hydraulic means for raising and lowering 100 the front part of the plow, a roller at the lower end of the hydraulic means for engaging the road surface, and means for actuating the hydraulic means from the tractor. 105

In testimony whereof I affix my signature.

JOHN H. WERTLEY.
